John H. Schell, 1636 N. Western Ave., Chicago, Ill.

Filed Nov. 7, 1962, Ser. No. 72,413

Term of patent 14 years

(Cl. D7—5)

FIG. 1

FIGURE 1 is a side elevational view of a twist heel showing my new design. The showing of a shoe is for purposes of illustration only, and

The dominant feature of the design resides in the portions shown in solid lines in the drawing.

I claim:

The ornamental design of a twist heel, substantially as shown and described.
